ILLUMINATED SIGN

Charles J. Wamser, Milwaukee, Wis.

Application September 23, 1935, Serial No. 41,771

2 Claims. (Cl. 40—130)

This invention pertains to illuminated signs, and more particularly to signs utilizing illuminated gas tubes for the characters or letters.

Serious difficulties encountered in signs of the foregoing type resulted in attempts to protect the tubes against the elements, and also obtain maximum effectiveness of the illumination in a simple and inexpensive structure. At the present time it is common practise in cheaper types of signs to mount the tubes on the outer face of the front panel of the sign, thus exposing the tubes to the elements, falling objects, and so on, and making the same very difficult to handle and ship without damage to the tubes. Furthermore, the effect obtained by a sign of the foregoing character is not the most desirable, inasmuch as the general outline of the characters formed by the tube is generally provided on the face of the sign, and, therefore, viewing the same from an angle, a double vision is obtained, and the characters become confused.

It is therefore the primary object of the present invention to provide an exceedingly simple and inexpensive sign employing illuminated tubes, in which the tubes are housed to protect them against damage from the elements, such as rain, snow, and hail, or other falling objects, as well as in shipping or handling, and at the same time provide a maximum illuminating effect.

Incidental to the foregoing, a more specific object of the invention is to provide a sign casing in which the illuminated tubes are mounted upon a supporting plate spaced rearwardly of the front panel of the casing to allow sufficient room for the bends required in forming various words or characters from a single tube, so that the strokes are uniform and distinct.

A still further object resides in closing the front of the sign when desired, by inexpensive transparent means, such as a thin glass panel, or one having raised portions formed therein and conforming in contour with the strokes of the tubes to increase their illuminating effect.

Another object is to provide a sign in which accessibility to the tubes is materially facilitated by the provision of a hinged front panel upon which the tubes may be supported.

With the above and other objects in view, which will appear as the description proceeds, the invention resides in the novel construction, combination, and arrangement of parts, substantially as hereinafter described, and more particularly defined by the appended claims, it being understood that such changes in the precise embodiment of the herein disclosed invention

may be made as come within the scope of the claims.

In the accompanying drawings are illustrated several complete examples of the physical embodiment of the present invention constructed according to the best mode so far devised for the practical application of the principles thereof.

Figure 1 is an elevation of a sign constructed in accordance with one form of the present invention.

Figure 2 is a fragmentary vertical section through the same, taken on the line 2—2 of Figure 1.

Figure 3 is an enlarged detailed section, taken on the line 3—3 of Figure 1, and illustrating the application of a transparent panel for covering the front cut-out panel.

Figure 4 is a fragmentary section of a modified form of the invention.

Figure 5 is an enlarged fragmentary detail illustrating the manner in which the tube is mounted behind the front cut-out panel.

Figure 6 is a side elevation of still another form of the invention, with parts broken away and in section.

Figure 7 is a vertical section of still another modification, and

Figures 8 and 9 are enlarged fragmentary detail sections illustrating modified forms of translucent panels which may be employed to house the illuminating tubes.

Referring now more particularly to the accompanying drawings, that form of the invention illustrated in Figures 1, 2, and 3 comprises a casing, indicated by the numeral 10, and including front plate 11, which forms a partial closure for the casing. The remaining portion of the casing is closed by a removable front panel 12 extending entirely across the casing, and secured thereto by bolts or screws 24, as will be herein-after described.

The front plate 11 is provided with a cut-out portion 13, in which a removable panel 14 is detachably secured. Both the panels 12 and 14 are provided with cut-out characters 16, conforming in contour to the strokes of the illuminating tubes 17 positioned rearwardly thereof. In order to support the tubes 17 the present form of the invention includes pans 18 bolted or otherwise secured to the front plate 11 of the casing, and spaced therefrom sufficiently to permit any arrangement of bends in the tube necessary to forming the letters or strokes of the characters in such a manner as to provide uniform single strokes defining clean-cut characters.

Figure 3 illustrates in detail the manner in which the pans 18 are attached to the front plate of the casing, as well as the method of attaching the removable panels 12 and 14, respectively, the 5 structures being identical, as shown in Figure 2. The pans 18 are provided with upper and lower flanges 19 and 20, respectively, both of which are secured to the front plate 11 by bolts 21. The top flange 19 is provided with an offset 22 10 spaced from the front plate 11 to permit insertion of an offset upper edge 23 formed on the panel 12. The lower end of the panel is secured to the flange 20 of the pan 18 by bolts 24.

As previously explained, the same structure is 15 employed in connection with the attachment of the panel 14, and also in that form of the invention illustrated in Figure 4, and in all instances where it is desired to employ removable cut-out front panels.

20 When it is desired to cover the cut-out portions 16 of the panels 12 and 14 by means of a translucent or transparent glass panel 25, as shown in Figure 3, the same is merely positioned back of the cut-out panels, and held in place 25 by clips 26 positioned between the cut-out panel and the adjacent pan, the clips being held in position by the attaching bolts for the panels.

Referring particularly to Figure 3, it will be noted that the tube 17 is secured to the pan 18 30 by a conventional tube support 27, which serves as an insulator, as well as a clamp, to which the tube is detachably connected. The electrodes 17' formed at the ends of the tubes may extend into conventional bushings 28 carried by the pans 35 or tube supports, or they may merely project through openings in the tube supports for attachment of the wires from the usual transformer.

In that form of the invention illustrated in 40 Figure 4, it will be noted that the individual pan for each set of tubes is eliminated, and a single partition 29, secured to the sides of the casing 10, serves as a support for the tubes.

Figure 6 illustrates a modification in which the casing 10', which in this particular instance is 45 designed for a double face sign, is provided with oppositely disposed closure plates 30 hingedly connected with the casing 10' at their lower edges, and locked in closed position by bolts 31, or any other suitable means, such as locks or latches. In this form of the invention it is proposed to support the tubes 17 upon the inner faces of the plates 30, which facilitates access to the tubes when the plates are swung downwardly 50 and supported in a horizontal position by chains 32, or other suitable connections. A particular advantage of this structure resides in the fact that the operator, in positioning the tubes upon the plates 30, has practically no difficulty in 55 properly alining the tube, such as might be encountered when the tubes are mounted upon a stationary support, and the cut-out closure for the panels are removable. While Figure 6 illustrates a double-face sign, it is to be understood that the same can be applied to a single-face sign, in which instance the central partition 29' 60 can be eliminated, as well as one of the hinged plates 30.

Figure 7 illustrates a modification of that 70 form of the invention shown in Figure 6, and differs therefrom only in that the tubes 17 are mounted upon the rear wall 33 of the casing 10''. In this arrangement the electrodes 17', formed at the ends of the tubes, do not extend through 75 the plate 33, but are laterally offset for connec-

tion with the transformer wires within the casing 10''.

If it is desired to elaborate upon the structure thus far described, instead of utilizing ordinary translucent or transparent panels for covering the illuminating tubes, in combination with cut-out panels of opaque material, it has been found that an improved illuminating effect can be obtained at very small additional cost by the provision of translucent or transparent panels 10 34 or 35 illustrated in Figures 8 and 9, respectively. The panel 34 is provided with a solid raised portion 34' corresponding in contour to the strokes of the tube 17, thus serving to diffuse and magnify the lighting effect of the tube, which 15 materially enlarges the appearance of the strokes, and renders the sign more attractive and distinctive at a maximum distance. The panel 35, illustrated in Figure 9, accomplishes similar results, although possibly not as effectively, by 20 means of the pressed out raised portion 35', instead of the solid raised portion 34'. The principal advantage of this type of panel resides in its reduced costs of manufacture.

From the foregoing explanation, considered in 25 connection with the accompanying drawings, it will be noted that an illuminated sign of exceedingly simple construction, and consequently low cost of manufacture, has been provided, which not only protects the illuminating tube against 30 damage from the elements, and in handling, but also obtains a maximum illuminating effect, in that the inherent brilliancy of the tube is not obstructed, and in view of the fact that ample space is provided for the tube, the same can be 35 bent in any desired form to provide uniform, clear-cut strokes, regardless of the contour of the characters or letters. As a simple example, Figure 5 illustrates one manner in which a plurality of letters may be formed from a single 40 tube, without duplicating any of the strokes.

It will also be appreciated that provision has been made to materially facilitate accessibility of the tubes, as shown in that form of the invention illustrated in Figures 6 and 7, wherein 45 the front of the casing is hingedly connected for attachment of the tubes directly thereto, or to a suitable stationary support within the casing. Lastly, the provision of a translucent or 50 transparent panel, such as illustrated in Figures 8 and 9, not only serves to completely protect the tubes against rain, snow, and moisture, but also materially enhances their illuminating effect.

I claim:

1. In an illuminated sign, a casing including a front wall having an opening, an opaque panel provided with cut-out characters and positioned in said opening, a pan detachably secured to the front wall at its upper and lower edges and to the bottom edge of said opaque panel, the upper edge of said panel being clamped between said front wall and pan, a translucent panel positioned at the rear of said opaque panel, and an illuminated tube carried by said pan in the rear of said translucent panel and comprising strokes conforming to those of the cut-out characters in the opaque panel.

2. In an illuminated sign, a casing including a front wall provided with an opening, an opaque 70 panel having cut-out characters positioned in said opening, a pan detachably secured to the front wall at its upper and lower edges and to the bottom edge of said opaque panel, the upper edge of said panel being clamped between said 75

front wall and pan, a translucent panel positioned in the rear of said opaque panel, clips secured between said opaque panel and said pan for retaining the translucent panel in position, 5 an illuminated tube positioned within said pan rearwardly of said translucent panel and com-

prising strokes conforming to those of the cut-out characters in said opaque panel, and detachable supports for said tube carried by said pan, the end terminals of said tube projecting through said pan.

5

CHARLES J. WAMSER.
